PANEL FASTENER

Herbert J. Woodall, Detroit, Mich., assignor to
 Woodall Industries Incorporated, Detroit,
 Mich., a corporation of Michigan

Application September 4, 1936, Serial No. 99,345

3 Claims. (Cl. 296—44)

My invention relates to an improved panel and support therefor. It is illustrated as embodied in a panel such as is used in the interior of automobile bodies. It resides in the provision of a fastener receiving part adapted to cooperate with a panel support constructed to receive the same.

5 Panels of this type are commonly formed of cardboard or other similar material which may be covered on the outer face with suitable trim 10 fabric. The cardboard foundation is ordinarily provided with fasteners which may be detachable therefrom and which are engageable with the support that is to carry the panel. These fasteners and the support adapted to receive the 15 same are commercially found in many different forms.

It is an object of my invention to provide a 20 panel foundation of this type with fasteners which project only a slight distance from the rear face thereof and which are readily engageable by manipulation of the panel with a relatively narrow panel supporting frame or ledge suitably apertured to receive fasteners. Preferably the 25 panel supporting element is provided with apertures that extend inwardly from its inner margin and through which the panel fasteners are slid to a point of engagement. A feature of importance is that the panel supporting element may be of relatively narrow width and the fasteners 30 are readily attachable therewith.

Another meritorious feature is that the fasteners may be fixed to the panel at the time of its fabrication and yet not project away from the rear face thereof to such a distance as to interfere with the stacking of the panels.

35 A further important characteristic is that the panel is not only readily attachable to its support but may also be readily detached therefrom.

Other important objects, features, and advantages 40 of this invention will more fully appear from the following description, appended claims, and accompanying drawing, wherein:

Figure 1 is a perspective of a fragment of a panel support and panel illustrating an embodiment 45 of my invention.

Fig. 2 is a cross sectional view through the structure shown in Fig. 1 with the panel illustrated as attached to the support whereas in Fig. 1 it is spaced therefrom.

50 Fig. 3 is a cross sectional view through the construction shown in Figs. 1 and 2 showing the method of securing the panel to the support.

Fig. 4 illustrates a modified form of construction of a panel support as compared with Fig. 1, 55 and

Fig. 5 is an elevation of a fragment of a panel support such as is shown in Fig. 1.

Panel supporting frames used in automobile body construction are commonly angular in cross section and in the several figures here shown the 5 panel supporting element is indicated generally as 10. It is provided with an angularly extending relatively narrow flange 12 which is turned inwardly and extends longitudinally thereof. The panel rests upon this flange and is secured 10 thereto. The outer sheet metal wall of the body is shown at 14.

Panels used commonly have a fiber board foundation. Such a foundation is indicated as 16. It is provided on its outer face with a suitable 15 trim fabric 18 which may be adhesively secured thereto and turned over the edges onto the rear face thereof. Padding may be provided if desired. The particular character of the trim or padding of the panel may be as desired. 20

It will be noted that the supporting frame is generally U-shaped and has opposed side flanges and a bottom flange which support the sides and bottom of the panel. The side flanges are provided with a plurality of apertures or slots indicated in Figs. 1 and 5 as 20. These apertures are there shown as extending inwardly from the inner margin of the flange transversely thereof for a limited distance and then extending substantially longitudinally thereof to a closed end 30 portion as shown particularly in Fig. 5. The apertures along the bottom flange are indicated as 22 and these extend from the upper margin downwardly transversely thereof. The apertures described are provided in such number as are 35 required to receive the desired number of fasteners to hold the panel in place and due to this extension inwardly from the margin of the flange such flange need not be of great width as it is only necessary that the aperture have a dimension sufficient to pass the relatively small diameter shank of the fastener. 40

The panel is provided with a plurality of headed studs 24 which project from its rear face. These studs may be secured to the panel in any 45 suitable fashion as shown in Fig. 2 wherein the stud is shown as fastened securely to the foundation board and as having a headed portion. The studs may be provided in such number as is desired to correspond with the fastener receiving 50 apertures of the flanges. In Fig. 1 the panel is shown as reversed and cut in half.

To secure the panel in place the studs on one side are moved into the slots of the flange on one side of the frame and the panel may then be 55

flexed along a vertical dimension so that the shanks of the studs on the other side may be received within the entrances to the apertures on such side as shown in Fig. 3. Upon flattening 5 out of the panel it is then moved downwardly, moving the shanks of the fasteners spaced along its bottom margin into the apertures 22 in the bottom flange and moving the fasteners along the side margins toward the closed ends of apertures 26. The garnish molding may then be secured 10 to the frame along the upper edge of the panel overlying the panel to hold it in place.

The construction shown in Fig. 4 differs in that the aperture 26 through the flange does not open 15 into the edge of the flange but has an upper end of sufficient width to pass the head of the stud which the lower end will not do. The aperture shown in Fig. 4 would preferably be provided in the side flanges only. The bottom flange would 20 be provided with apertures such as 22 shown in Fig. 1. The method of installation would be substantially the same except that it would not be necessary to flex the panel and the heads of the fasteners would be moved directly through 25 the enlarged upper ends of the apertures in the side flanges and then moved downwardly to be engaged at the lower end to retain the panel in place.

It will be seen that the panel may be quickly 30 attached to its supporting frame and will be securely held thereto. It likewise may be released therefrom. The headed fasteners project only a short distance away from the rear face of the panel and do not obstruct the stacking of the 35 panels. In the construction shown in Figs. 1 and 5 the movement of the panels downwardly into position would tend to tension them transversely as the apertures 20 throughout this longitudinal extent extend somewhat angularly with 40 respect to the margin of the flange.

The slots 20 and 22 and the lower ends of apertures 26 preferably have a width greater than the diameter of the studs 24 so that flotation therein is permitted to accommodate for 45 expansion or contraction of the panel.

What I claim is:

1. In combination with a panel support comprising spaced side frame members each provided with a plurality of fastener receiving apertures spaced apart longitudinally of the member, each aperture extending inwardly from the inner margin of the member transversely thereof and then longitudinally of the member, and a panel provided along each side margin with a row of headed fasteners projecting away from the rear face, said rows being spaced apart a distance greater than the inner margins of said side frame members, each fastener having a shank movable through the entrance of the corresponding fas-

tener aperture in the side frame member transversely of the member and then longitudinally into a position of engagement of the head of the fastener therewith.

2. In combination, a U-shaped panel supporting frame having relatively narrow panel supporting sides and bottom, the opposite sides of the U provided with fastener receiving slots spaced apart longitudinally thereof and extending initially inwardly from the inner margin transversely of the side and then longitudinally and angularly of the side toward the outer margin thereof, the bottom of the U frame provided with fastener receiving slots spaced apart longitudinally thereof and extending inwardly from the inner margin transversely and toward the outer margin thereof, and a trim panel provided along its bottom margin and along its side margins with headed fasteners spaced apart longitudinally of the margins corresponding to the slots in the bottom and sides of the U frame, said fasteners projecting away from the rear face of the panel and each having a shank receivable through the entrance to the corresponding fastener slot in the U frame and movable therethrough to a position of engagement of the head of the fastener therewith, the distance transversely across the panel between the headed fasteners along one side margin and the headed fasteners along the opposite margin being greater than the distance transversely across the U frame between the entrances into the fastener receiving slots along one side of the frame and entrances into the fastener receiving slots along the opposite side of the frame.

3. In combination, a pair of spaced apart supporting frame elements, each frame element provided with a row of apertures which apertures are spaced apart longitudinally of the frame element, each aperture extending transversely of the frame element and having a fastener receiving entrance at its inner end, a panel shaped to be supported on said frame elements and provided along each of the two opposite margins which seat upon said frame elements with a row of headed fasteners projecting away from the rear face of the panel and spaced apart to correspond with the spacing of the apertures in the frame elements, a row of fasteners along one of said margins being spaced from the row of fasteners along the other of said margins a distance greater than the distance between the inner ends of the apertures in one row and the inner ends of the apertures in the other row, said fasteners being receivable into the apertures through the inner ends thereof and movable therethrough into engagement with the frame elements.

HERBERT J. WOODALL.
